UNITED STATES PATENT OFFICE.

CONRAD BAUMGARTNER, OF SCHENECTADY, NEW YORK, ASSIGNOR TO GENERAL ELECTRIC COMPANY, A CORPORATION OF NEW YORK.

AUTOMATIC PNEUMATIC FEED FOR PUNCH-PRESSES.

1,001,606.

Specification of Letters Patent. Patented Aug. 29, 1911.

Application filed January 30, 1908. Serial No. 413,371.

To all whom it may concern:

Be it known that I, CONRAD BAUMGARTNER, a citizen of the United States, residing at Schenectady, in the county of Schenectady 5 and State of New York, have invented certain new and useful Improvements in Automatic Pneumatic Feeds for Punch-Presses, of which the following is a specification.

This invention relates to devices for automatically feeding material to a machine, and its special object is to feed sheet metal to a 10 punching press, although applicable to a wider range of uses. For the sake of simplicity, however, I shall describe it as applied to a sheet metal punching press. In feeding the sheets of metal to such a machine by hand, there must always be more or less waste, owing to the impossibility of moving the sheet forward exactly the same 15 distance for each operation of the dies. Hand feeding is, moreover, liable to be slow, so that there is a loss of time in addition to the waste of material. In modern shop practice, the operations are conducted on 20 such a large scale that the small leaks are well worth looking after, and the object of my invention is to obviate the loss of stock and the time above noted, by providing a 25 feeding mechanism which automatically advances the sheet of metal exactly the right 30 distance at each stroke of the press to enable the dies to make a perfect punching without wasting more than a minimum of stock between two punchings. The mechanism also 35 works rapidly and constantly.

In case there is not enough stock left at the end of a sheet to make a perfect punching, the mechanism automatically makes a longer stroke, so as to pass this insufficient 40 portion beyond the dies and permit the end of a new sheet to be brought under them. Other details of operation will be brought out in the following detailed description.

The mechanism which forms the subject- 45 matter of this application comprises one or more pistons operated by fluid pressure in a suitable cylinder, a rod reciprocated by said piston or pistons, gripped fingers carried by said rod for seizing the edges of the

sheet of metal, and valve mechanism for admitting fluid pressure to said cylinder and exhausting it therefrom at the proper times in the operation of the press; it being understood of course that the sheet metal is advanced by the feeding mechanism between the strokes of the dies. 50

In the accompanying drawings, Figure 1 is a side elevation of a punching press equipped with my improved automatic pneumatic feed; Fig. 2 is a longitudinal 60 section of the cylinder and its pistons; Fig. 3 is a front elevation of the valve with its cover removed; Fig. 4 is a cross section of said valve, complete; Fig. 5 is a perspective view of the wear plate in said valve; Fig. 6 65 is a perspective view of the valve proper; Fig. 7 is a sectional view of the clutch for holding the stop plug in place; Fig. 8 is a perspective view of the check valve and its controlling handles; Fig. 9 is a side elevation of the clutch-operating devices; Fig. 10 is a front elevation of the same; Fig. 11 is a front elevation of the rear grippers; Fig. 12 is a sectional elevation of the front gripper; Fig. 13 is a sectional elevation of 70 75 one of the rear grippers; and Fig. 14 is a perspective view of the front gripper and the stop pin.

Attached to the frame 1 of the punching press is a horizontal cylinder 2 whose axis 80 is parallel with the line of the feed. Stout guides 3 are secured to the frame parallel with the cylinder, and on these guides are mounted frames extending transversely of the line of feed and secured to the opposite 85 ends of the piston rod 4 which runs through the cylinder 2 and carries the two pistons 5 6. These pistons are located on opposite sides of a stationary partition or internal head 7, secured in the cylinder about midway between its ends, and containing a central aperture for the piston rod, which has a sliding fit therein. By admitting fluid pressure into the cylinder on opposite sides of the partition or head 7, alternately, and 90 between said head and the pistons, the latter and the piston rod to which they are attached, will be moved to and fro, causing 95

the transverse frames to slide back and forth on the guides. These frames carry the grippers which seize the sheet metal and feed it to the dies.

- 5 I will first describe in detail the cylinder and its appurtenances. Said cylinder is preferably provided with a bushing 8, which projects beyond the ends of the cylinder and receives at one end a screw-threaded sleeve 11 abutting against the adjacent end of the cylinder. At the other end, the bushing receives a union 10 which is screw-threaded thereon and retains in place a screw-threaded sleeve 11 rotatable on said bushing and meshing with screw-threads on the interior of a circular frame 12 which has an eye 13 clamped by a bolt 14 on the guide 3. A lock-nut 15 on the threaded sleeve 11 presses against one end of said circular frame. In 10 the walls of the frame 12 are slots 16 through which extend latches 17 pivoted to said frame at 18 and urged inwardly by leaf springs 19. These latches serve to lock in place, in this end of the bushing, a tubular plug 20 concentric with the piston rod 4, which acts as a stop to limit the movement of the piston 6 and the piston rod. The plug is preferably adjustable along the piston rod, as for instance by means of a nut 21 and lock nut 22 screwed upon the exterior of said plug; the nut 21 containing a circumferential groove 23 in which the latches 17 engage. A further function of this plug will be described later.
- 35 Fluid pressure, preferably compressed air, is supplied to the cylinder 2 through a pipe 24 which communicates with a valve chest 25 through a suitable shut-off cock 26. The air must be maintained at or above a predetermined minimum pressure to effect a proper operation of the mechanism, and in case it falls below this minimum a signal is arranged to warn the attendant, preferably a whistle 27. The valve chest contains a cylindrical chamber 28, closed by a head 29 and containing a circular disk valve 30 which is mounted on or formed integral with a shaft 31 journaled in the back wall and the head of the chest. A spring 32 encircles the shaft inside the chest and presses the valve against a stationary plate 33 of brass or other suitable material serving as a wear plate and also as a seat for the valve. In the plate 33 are three ports, 34 35 36, the first communicating with a pipe 37, leading to the admission port 38 near the head 7 in the cylinder 2; the second communicating with a similar pipe 39 leading to the port 40 in said cylinder, and the third connecting with an exhaust pipe 41. In the valve disk are two through ports 42 43 arranged to be brought in line with the ports 34 35 by oscillating the shaft 31. Between these ports 42 43 is a recess 44 adapted to connect

either of the ports 34, 35 with the exhaust 65 port 36. The valve 30 also contains a recess preferably composed of three circular depressions 45 connected by grooves 46, and communicating with the chamber 28 by one or more holes 47. In the face of the seat 33 70 are formed two grooves 48 which are brought alternately into communication with the recesses 45 at the ends of the oscillations of the valve. These recesses and grooves admit compressed air between the valve and its 75 seat to serve as a lubricant. The valve is oscillated by means of a crank arm 49 on the shaft 31 outside of the valve chest. A pitman 50 connects this crank with a wrist pin 51 on the main shaft 52 of the press. 80 The pitman is preferably connected with the crank by a lost-motion device in order to produce a dwell at each end of the stroke of the valve. In Fig. 1 the crank is shown as pivotally connected to a sleeve 53 through 85 which slides a nut 54 adjustable on the pitman and having at each end a flange 55 which strikes the sleeve and causes the crank to move, the space between the flanges being greater than the length of the sleeve. 90

In each of the pipes 37 39 is a check valve 57 opening toward the cylinder 2. In order to permit the escape of the air which is admitted to the cylinder through these pipes, an exhaust port 58 is located a little distance 95 away from the head 7 in each end of the cylinder and a branch pipe 59 is shunted around the check valve 57 from each of the pipes 37 39 to said port. In each branch pipe is a check valve 60 opening away from 100 the cylinder 2.

When the parts are in the positions shown in Figs. 1, 2 and 3, the air will pass through the ports 42, 34, the pipe 37 and the port 38 to the left hand end of the cylinder as shown 105 in Figs. 1 and 2, forcing the piston 5 to the left. Meanwhile the exhaust port 58 in the other end of the cylinder has been put in communication with the escape pipe 41 through the pipe 39, the port 35, the recess 110 44 and the port 36. When the piston 6 moves over the port 58 to the position shown in Fig. 2, it cuts off the exhaust through said port, but the air imprisoned between said piston and the head 7 can escape slowly 115 through a pet cock 61 on the pipe 39 below the check valve 57, thus causing a cushioning effect on said piston.

Having thus ascertained how the pistons are caused to reciprocate the rod 4 in synchronization with the rotation of the main shaft of the press, and at the times when the wrist pin on said shaft is passing its upper and lower dead points, I will now take up the grippers which seize and carry the sheet metal to the dies. Each gripper comprises a casting 62 adapted to be fastened to a transverse frame secured to

the piston rod 4. In the drawings, these frames consist of two parallel rods or tubes 63, and the casting 62 has two parallel holes to receive these tubes, the material between 5 said holes being slotted out to enable a binding screw 64 to clamp the casting firmly in place on said tubes. The casting carries an overhanging upper jaw 65, and its lower part contains a cylinder in which is located 10 a piston or other movable abutment 66, on which is supported a lower jaw 67. Springs are arranged to urge said lower jaw open, as for instance the springs 68 engaging with the headed pins 69 which extend from said 15 jaw down into sockets in the casting. The lower end of the cylinder is connected by a pipe 70 with the compressed air supply, so that when air is admitted under the piston or other abutment the lower jaw will be 20 raised and the two jaws will grip the edge of the sheet 71 of metal, which is to be fed to the dies.

The admission of air to the abutments of the grippers is preferably controlled by the 25 main valve in the following manner. From the pipe 37, which supplies air to the piston 5 which effects the forward feed of the sheet, branch pipe 72 leads through a stop valve 73 to a pipe 74 from the ends of which 30 flexible hose-pipes 75 run to the pipes 70. The instant air is admitted to the pipe 37, it not only causes the feeding stroke of the piston rod 4, but it also closes the grippers on the edges of the sheet metal, so that the 35 latter is carried forward with the rod. There are preferably three grippers; one at the front and two at the rear of the dies, the latter being on opposite sides of the sheet, but both carried on the same frame; 40 as shown in Fig. 11. This frame also carries a transverse rock shaft 76 to which are secured resilient fingers 77 resting on the upper surface of the sheet metal. At one end of the shaft is a rock arm 78 adapted 45 to come in contact with a stationary tappet 79, which is adjustably secured by the screw 80 to the frame of the press. When this shaft is rocked by the tappet the fingers press down on the blanks punched from the 50 sheet and force them to fall into the receptacle provided for that purpose. This prevents any blanks from sticking in the sheets and going into the waste.

In order to properly position the sheets 55 when they are fed into the machine, and insure that they shall be presented to the dies in such a way that the first blank punched will come close to the end of the sheet, a stop pin 81 is provided in the front gripper. 60 This pin has a base 82 containing a slot to receive a clamping screw 83 so that the pin can be adjusted for different kinds of work. When the lower jaw of the gripper rises to seize the sheet, it lifts said sheet above said

pin, so that the pin offers no obstruction to 65 the onward feed of the sheet, in subsequent operations.

It frequently happens that the sheets of metal are not quite long enough to provide for a punching close to the rear end thereof, 70 but a certain amount of waste is necessary. In order to prevent the making of imperfect punchings at the ends of such sheets, and at the same time insure a sufficient forward feed of the incoming fresh sheet to bring 75 it fully under the dies, it is necessary to provide for a stroke of the feeding mechanism long enough to make up for the additional amount of waste in the length of the old sheet. To cause this to take place automatically, I unlatch the stop plug 20, so that at the next back stroke of the piston rod the air pressure will force the plug out of the cylinder 2 until it is stopped by the collar 84 on said rod; said collar being set at the 80 same distance from the outer end of the plug as the space between the head 7 and the piston 5. Inasmuch as the rod is not checked by the plug, it will move backward until the piston 5 cushions against the head 90 7. The extent of this movement can be adjusted by adjusting the piston 5 along the rod; the hub of the piston being preferably screw-threaded to mesh with screw threads on the rod, and provided with a tapering 95 end on which a clamping nut 85 is placed.

In order to unlatch the plug, the latch levers are pivotally connected at their free ends with movable abutments, such as pistons 86 in a cylinder 87. When compressed 100 air is admitted between said pistons they will be forced apart and the latches will be withdrawn from the circumferential groove 23 in the nut 21 on the plug. The air is led to this cylinder 87 by a hose 88 branching 105 off from the main air pipe 24 at a point above the valve chest 25, and being itself controlled by a valve 89, which is held normally closed by a spring 90 bearing on its handle 91. Adjacent to this handle is 110 mounted a rock shaft 92 carrying a finger 93 which lies under said handle. The shaft also has a rock arm 94 on which is secured a bar 95. A longitudinal slot 96 in the bar and a clamping screw 97 enable the bar to 115 be properly adjusted. At the lower end of the bar there is pivoted a long hook 98 which rests on the surface of the metal sheet 77. The hook extends toward the dies of the press, and its other end, on the opposite side of the pivot, is connected by a light spring 99 with a stud 100 on the upper end of the bar. This spring urges the hook downwardly upon the surface of the metal sheet. As a new sheet of metal is started 120 along through the press its end encounters and engages with this hook, carrying it toward the dies and swinging the bar to an 125

upright position as shown by the dotted lines in Fig. 9. In this movement, the screw 101 carried in a lug 102 on the bar comes in contact with the hook and causes its end 5 to lift away from the sheet of metal so that said sheet is free to pass on through the press. In this dotted line position of the bar the finger 93 on the rock shaft 92 will have raised the handle of the valve 89 10 against the tension of the spring 90, thereby opening said valve and admitting compressed air to the cylinder 87. The movable abutments 86 are thereby forced apart, and the latches are withdrawn from the groove 15 in the nut 22 on the plug 20. On the next backward stroke of the piston rod 4, the piston 6 will strike the plug and carry it out of the cylinder 2 to the position shown in Fig. 1, at which point the piston 5 comes 20 in contact with the stationary head 7. The abnormal length of the backward stroke thus permitted, enables the rear grippers to take hold of the sheet of metal 77 far enough back of their usual point of operation to 25 enable them to pull the rear end of the sheet being operated on completely past the dies, so that there will be no danger of an imperfect punching being made in the insufficient stock that remains at the end of the 30 sheet. At the same time, the front grippers carry the fresh sheet forward such an amount as to insure its end passing fully beyond the dies at the next feeding stroke, so that the first punching made in that 35 sheet will be sure to come entirely within it.

The action of the valve 89 is only momentary, because the spring 90 closes this valve as soon as the hook is raised out of engagement with the end of the sheet. In 40 closing the valve, the spring also acts to return the bar 95 to the position shown in full lines in Fig. 9, except that the hook will rest on the upper surface of the sheet passing under it, being ready to drop over the 45 end of a new sheet, as shown. The extent of angular movement of the rock shaft, is limited by an arm 103 thereon, which comes into contact with a detent stud on the frame of the press when the parts return to their 50 normal position. The movement of the valve which shuts off the air from the cylinder 87 also serves to open an exhaust port from said cylinder, so that the springs 19 can return the latches to their locking position 55 in the groove 23, when the plug is carried into the cylinder 2 by the feeding stroke of the piston rod 4. It will thus be understood that the operation of this part of the apparatus is intermittent, taking place 60 only when a fresh sheet is fed into the press. The quantity of waste in any given sheet depends upon the size of the punching that is being cut therefrom, so that for each change in the dies the piston 5 must be adjusted to 65 produce the proper length of abnormal

stroke when the plug 20 is unlatched. The stop pin 81 must also be adjusted so that the entering end of the fresh sheet will be in proper relation to the dies.

The operation of the several parts of the 70 machine has been described in connection with their construction, but it may be said by way of recapitulation that the sheets of sheet metal are automatically fed to the dies by the grippers 62 carried on the piston rod 75 4, which is reciprocated by the pistons 5 6 in the cylinder 2. Compressed air is admitted to the cylinder by an oscillatory valve 30 actuated by a crank 49 and a pitman or connecting rod 50 which has a certain amount of lost motion, so that the sheet is held firmly during the cutting stroke of the dies and until they have separated sufficiently to clear the sheet; after which the valve is moved and the open grippers are 80 slid back to take a new hold on the edges of the sheet. Shortly after the upper die begins to descend the valve is reversed and the grippers close on the sheet and move it forward to present a fresh surface to the 85 dies. The grippers are opened and closed by compressed air, and are controlled by the same valve which controls the air supply to the cylinder 2. The normal stroke of the grippers is just enough to enable each punching to come close to the one preceding it 90 without undue waste. In case there is danger of an imperfect punching at the end of the sheet, the plug 20, which limits the feeding stroke of the grippers, is unlatched and 95 the grippers are permitted to slide back an abnormal distance to give a longer feed and thereby cause the end of the old sheet to skip the dies. This is automatically effected by a hook adapted to engage with the entering end of a new sheet, said hook controlling 100 an air valve which admits air to movable abutments by means of which the latches holding the plug are released, for that stroke. In case the attendant wishes to stop 105 the feed at any time, he can shut off the supply of air to the grippers by means of the valve 73 in the pipe 72; said valve being held normally open by a spring 104, and provided with handles 105 located conveniently within reach of the attendant. 110

What I claim as new and desire to secure by Letters Patent of the United States, is,

1. The combination with a punching press, of pneumatic means for automatically gripping the sheet of metal to be fed to the dies, and pneumatic means for automatically advancing said gripping means to carry said sheet under said dies. 120

2. The combination with a punching press, of a set of grippers to feed a sheet of metal to the dies of said press, a rod for actuating said grippers, and a movable abutment responsive to fluid pressure and connected with said rod. 125

3. The combination with a punching press, of a set of grippers to feed a sheet of metal to the dies of said press, a rod for actuating said grippers, a piston attached to said rod, 5 and a cylinder containing said piston.
4. The combination with a punching press, of a set of grippers to feed a sheet of metal to the dies of said press, a rod for actuating said grippers, pistons attached to said rod, 10 a cylinder containing said pistons, and a valve controlling the admission of fluid pressure to said cylinder.
5. The combination with a punching press, of a set of grippers to feed a sheet of metal to the dies of said press, a rod for actuating 15 said grippers, pistons attached to said rod, a cylinder containing said pistons, a valve controlling the admission of fluid pressure to said cylinder, and means for operating 20 said valve in synchronism with the dies.
6. The combination with a punching press, of a cylinder parallel with the line of feed to the dies of said press, pistons in said cylinder, a piston rod, grippers adapted to 25 seize the edges of the sheet and mounted on said rod, movable abutments for operating said grippers, and a valve controlling the admission of fluid pressure to said cylinder and to said abutments.
- 30 7. The combination with a punching press, of a cylinder parallel with the line of feed to the dies of said press, a stationary head in said cylinder, a piston rod passing through said cylinder and head, pistons on said rod 35 on opposite sides of said head, a valve for controlling the flow of fluid pressure to said cylinder on opposite sides of said head, and grippers carried by said piston rod.
8. The combination with a punching 40 press, of pneumatic means for feeding a sheet of metal to the dies of said press, and means for automatically varying the stroke of said feeding means.
9. The combination with a punching 45 press, of pneumatic means for feeding a sheet of metal to the dies of said press, and means whereby an entering sheet is caused to vary the stroke of the feeding means, in order to avoid imperfect punchings.
- 50 10. The combination with a punching press, of pneumatic means for feeding a sheet of metal to the dies of said press, a stop for determining the stroke of said feeding means, and means for automatically 55 withdrawing said stop when a new sheet enters the press.
11. The combination with a punching 60 press, of pneumatic means for feeding a sheet of metal to the dies of said press, an adjustable stop for limiting the normal stroke of said feeding means, and means for automatically withdrawing said stop when a new sheet enters the press.
- 65 12. The combination with a punching 65 press, of feeding means comprising a cylinder, a stationary head therein, a piston rod, pistons thereon on opposite sides of said head, and an adjustable plug in one end of said cylinder serving to limit the movement of said rod and pistons. 70
13. The combination with a punching press, of feeding means comprising a cylinder, a stationary head therein, a piston rod, pistons thereon on opposite sides of said head, an adjustable plug in one end of said cylinder serving to limit the movement of 75 said rod and pistons, and means for automatically releasing said plug to permit said rod to make an abnormal stroke.
14. The combination with a punching 80 press, of feeding means comprising a cylinder, a stationary head therein, a piston rod, pistons thereon on opposite sides of said head, one of said pistons being adjustable lengthwise of said rod, a plug coöperating 85 with the other piston to limit the normal stroke of the rod, and means for automatically withdrawing said plug to permit the adjustable piston to govern the stroke.
15. The combination with a punching 90 press, of feeding means comprising a cylinder, a piston rod and piston therein, a plug in one end thereof, a clutch for holding said plug in place, and means for automatically 95 releasing said clutch.
16. The combination with a punching 100 press, of feeding means comprising a cylinder, a piston rod and piston therein, a tubular plug in one end thereof, a latch engaging 100 with said plug, a movable element adapted to be engaged by a sheet of metal entering the press, and connections between said element and the latch for disengaging the latter from the plug.
17. The combination with a punching 105 press, of feeding means comprising a cylinder, a piston rod and piston therein, a tubular plug in one end thereof, a latch engaging 110 with said plug, a movable element adapted to be engaged by a sheet of metal entering the press, connections between said element and the latch for disengaging the latter from the plug, said connections comprising a movable abutment responsive to 115 fluid pressure, and a valve operated by said movable element and controlling a supply of fluid pressure to said abutment.
18. The combination with a punching 120 press, of feeding means comprising a cylinder, a piston rod and piston therein, a tubular plug in one end thereof, a latch engaging 120 with said plug, a hook adapted to be engaged by the end of a sheet of metal entering the press, means for disengaging said hook after said sheet has moved a short distance, and fluid pressure connecting mechanism between said hook and said latch operating to release the plug when said hook is actuated.
19. The combination with a punching 125 press, of feeding means comprising a cylinder, a piston rod and piston therein, a tubular plug in one end thereof, a latch engaging 125 with said plug, a hook adapted to be engaged by the end of a sheet of metal entering the press, means for disengaging said hook after said sheet has moved a short distance, and fluid pressure connecting mechanism between said hook and said latch operating to release the plug when said hook is actuated.

press, of pneumatic feeding means for the sheet metal, comprising a reciprocable rod, pistons for actuating said rod by fluid pressure, grippers mounted on said rod and operated by fluid pressure, and means for preventing the operation of the grippers without stopping the reciprocation of said rod.

In witness whereof, I have hereunto set my hand this 28th day of January, 1908.

CONRAD BAUMGARTNER.
